UNITED STATES PATENT OFFICE.

JOHN A. GRIFFIN, OF LOS ANGELES, CALIFORNIA.

CONCRETE FENCE-POST.

1,020,412.

Specification of Letters Patent. Patented Mar. 19, 1912.

Application filed August 21, 1911. Serial No. 645,306.

To all whom it may concern:

Be it known that I, JOHN A. GRIFFIN, a citizen of the United States, residing at Los Angeles, in the county of Los Angeles and 5 State of California, have invented new and useful Improvements in Concrete Fence-Posts, of which the following is a specification.

My invention relates to improvements in 10 fence posts made of concrete or other plastic material.

The object of my invention is to provide 15 a simple, inexpensive post of great durability, provided with novel means for easily 20 and conveniently securing and removing either wood or wire fences without the use of nails, which objects, I accomplish by the arrangement and combination of parts as will be hereinafter more fully described and 25 finally pointed out and claimed.

In the accompanying drawing, which forms a part of this specification, Figure 1 is a side elevation of the post upon which the fence is secured, Fig. 2 is an end elevation of Fig. 1, and Figs. 3 and 4 are cross sections through my post, showing in plan the method of securing wood or wire fences 30 respectively.

Similar numerals of reference denote like 35 parts throughout.

The post consists of a body 1, having an enlarged bottom 2, the object of which is to give it greater bearing surface and also to prevent it from being easily removed when 40 set in the ground. In the body 1, a plurality of longitudinal reinforcing rods or wires 3 are embedded which wires extend from the top to the bottom and are located, preferably, as shown, in Figs. 3 and 4. Also embedded in the post 1, or secured in the holes 5, therein, which holes 5, are left in the post when it is molded, are the loop or eye rods 4, or 4' for supporting the fencing. It is, of course, understood that I may use either or 45 both the types of loop eyes and make the same of any suitable size or material, the preferable type, however, being that shown in Fig. 3, where the holes are left through the post and the loop eyes threaded therein 50 after the post has set or seasoned, and the ends 6, thereof, bent outwardly in opposite directions replacing the rods 4'.

To secure a wood fence to the post the boards 13, are placed in the space between two sets of loop eyes 4 or 4' and an inverted 55 U-shaped rod or wire 8, is inserted through the upper and lower sets of said loop eyes, across the outside face of the said boards 13, and its ends bent to hold it in place as clearly shown in Figs. 1, 2 and 3. Where the ends 60 of two boards meet on a post, as at 11, Fig. 1, staples 12, are driven into the ends of the boards over the rods 8, to secure the same in their proper positions as clearly shown in Figs. 1 and 2.

To secure a wire fence to the post the wires 10, are laid upon the loop eyes 4, or 4' and staples 9, are placed down over the wire through the eyes and the ends of said staples bent to secure them in their desired position 70 as clearly shown in Figs. 1, 2 and 4.

What is claimed is:—

1. A fence post having an upper and a lower pair of eyes secured thereto, a board arranged between said pairs of eyes, and a 75 U-shaped rod threaded through all of the eyes and having its free ends bent at right angles to engage beneath one of the pairs of eyes.

2. A fence post having an upper and a 80 lower pair of eyes secured thereto, a board engaged between said pairs of eyes, a U-shaped rod threaded through all of the eyes and engaging across the face of the board, and staples straddling the legs of the U- 85 shaped rod and driven into the board.

3. A fence post having an upper and lower pair of eyes secured thereto, a pair of boards having their ends in abutting engagement and located between the eyes, a U-shaped 90 rod threaded through all of the eyes and having one leg engaging across the end of one board and its other leg engaging across the other board, and staples straddling said legs and driven into the respective board 95 ends.

In testimony whereof I have hereunto set my hand in presence of two subscribing witnesses.

JOHN A. GRIFFIN.
